PLATE FOR PASSOVER SERVICE

Edna Earl Fincher, Longview, Tex.

Application January 26, 1956, Serial No. 39,938

Term of patent 14 years

(C1, D44—15)

The figure is a plan view of a plate for passover service, showing my new design, the plate being substantially flat and of conventional thickness. The dominant features of my design reside in the portions shown in full lines on the drawing.

I claim:

The ornamental design for a plate for passover service, as shown and described.
